CLAIM

The ornamental design for a combined meter and electrical outlet housing, as shown and described.

DESCRIPTION

FIG. 1 is a front view of the combined meter and electrical outlet housing showing my new design;
FIG. 2 is a back view thereof;
FIG. 3 is a top view thereof;
FIG. 4 is a bottom view thereof; and
FIG. 5 is an end view, the other end view being a mirror image of FIG. 5.

FIG. 1

FIG. 2

FIG. 3

FIG. 4
